(Cl. D74—1)

To all whom it may concern:

Be it known that we, Edward D. Davis and Norbert Shaeffer, citizens of the United States, residing in Chula Vista, in the county of San Diego and State of California, and Los Angeles, in the county of Los Angeles and State of California, respectively, have invented a new, original, and ornamental Design for a Combined Palette and Water Jar, of which the following is a specification, reference being had to the accompanying drawings, forming a part thereof:

We claim:

The ornamental design for a combined palette and water jar, substantially as shown.

EDWARD D. DAVIS.

NORBERT SHAEFFER.
